UNITED STATES PATENT OFFICE.

ROCCO DELEWESE, OF COLUMBUS, OHIO.

INTERNAL-COMBUSTION ENGINE.

1,280,181.

Specification of Letters Patent.

Patented Oct. 1, 1918.

Application filed August 17, 1917. Serial No. 186,792.

To all whom it may concern:

Be it known that I, Rocco DELEWESE, a citizen of the United States, residing at Columbus, in the county of Franklin and 5 State of Ohio, have invented certain new and useful Improvements in Internal - Combustion Engines, of which the following is a specification.

My present invention pertains to internal 10 combustion engines and more particularly to means appurtenant to internal combustion engines for preparing fuel for consumption therein.

The general object of my said invention is 15 to provide a simple, compact and inexpensive combination for utilizing to the best advantage the heat values, afforded by an engine in operation, in raising the temperature of the air commingled with hydrocarbon 20 to form an explosive mixture, so that the comparatively inexpensive kerosene of commerce may be used as a fuel, in lieu of gasoline, for the efficient operation of the engine.

25 To the attainment of the foregoing the invention consists in the peculiar and advantageous instalment hereinafter described and definitely pointed out in my appended claims.

30 In the accompanying drawings which are hereby made a part hereof:

Figure 1 is a view showing so much of an internal combustion engine as is necessary to illustrate the application of my improved 35 means; the said view including the engine cylinder in transverse section and my novel instalment in plan or elevation according to whether the cylinder is disposed vertically or horizontally.

40 Fig. 2 is a detail transverse section taken in the plane indicated by the line 2—2 of Fig. 1.

Similar numerals of reference designate 45 corresponding parts in both views of the drawings.

The engine cylinder 1 incloses the usual explosion chamber 2, and communicating with the said chamber 2 in the ordinary, well known manner is a carbureter 3 which 50 *per se* may be of the usual type or of any other construction compatible with my purpose of my improvement.

Connected to the liquid fuel duct of the carbureter 3 is a conduit 4 with which are 55 connected branch conduits 5 and 6, equipped with cut-off valves 7 and designed to be

connected with a kerosene tank and a gasoline tank, respectively.

In communication with the explosion chamber 2 at a point diametrically opposite 60 the carbureter connection or explosive-mixture inlet, or approximately so, is a lateral arm 8^a on a jacket 8 of about the proportional transverse size illustrated. The said jacket 8 is preferably, though not necessarily, of cast iron, is closed at its ends, as indicated by 9 and 10, and is provided adjacent to its end 10 with a lateral exhaust outlet 11 which may be directly connected with the atmosphere or may be connected 65 through a pipe as shown with a remote point of discharge, in the discretion of the party practising my invention.

In furtherance of my invention, the jacket 8 is curved lengthwise through a considerable 70 part of a circle, and throughout its length it is arranged in close proximity to the outer side of the wall of the cylinder 1, this in order to assure the jacket being exteriorly heated to a considerable extent by 75 the heat radiated from the said cylinder wall.

Also in furtherance of my invention a pipe 12 of about the proportional diameter 80 illustrated and having a thin wall is carried longitudinally through the jacket 8 and beyond the ends 9 and 10 thereof. One of the extended ends of the said pipe 12 is open 85 to the atmosphere, and the other extended end thereof is connected through a pipe 13 90 with the interior of the carbureter 3.

With the further statement that the carbureter 3 is connected with the explosive mixture inlet port of the combustion chamber 2, and the jacket arm 8^a is connected with 95 the exhaust port of said chamber, the operation and the practical advantages of my novel instalment will be fully understood from the following:

In starting the engine the valve in conduit 100 5 is closed and the valve in conduit 6 is opened, and the engine is operated with gasoline as a fuel for a short period, say five minutes or sufficiently long to highly heat the cylinder 1 and the jacket 8, and give 105 rise to the passage of a considerable volume of highly heated products of combustion through the jacket and the consequent high heating of the thin wall pipe 12. The valve in conduit 6 is then closed and the valve in 110 conduit 5 is opened so as to establish the supply of kerosene instead of gasoline to

the hydrocarbon fuel duct of the carbureter 3, whereupon, by reason of the highly heated jacket 8 and pipe 12 and the heat values given off by the products of combustion passing through the jacket and surrounding the pipe 12, the air will be considerably expanded *en route* to the carbureter with the result that when such expanded air is commingled with the kerosene an explosive-mixture is formed equal in efficiency to that produced by the mixture of atmospheric air with gasoline, and thereafter the engine is operated by the combustion of the mixture formed by highly heated and expanded air commingled with kerosene.

10 The practical advantages of my novel instalment will be fully appreciated when it is stated that in actual work I have developed as much power with an engine equipped 20 with my improvement and using kerosene as a fuel as can be developed with an ordinary engine using gasoline as a fuel, and the economy of an engine carrying my improvement will be apparent when the fact is cited 25 that the market price per gallon of kerosene is less than one-half of that of gasoline.

I have entered into a detailed and explicit description of the construction and relative 30 arrangement of the parts embraced in the present and preferred embodiment of my invention in order to impart a full, clear and exact understanding of the said embodiment. I do not desire, however, to be 35 understood as confining myself to the said specific construction and relative arrangement of parts since it is to be understood that in the future practice of the invention such changes or modifications in the form, 40 arrangement and proportion of parts may be made as are fairly comprehended by my invention as defined in my appended claims.

Having described my invention, what I

claim and desire to secure by Letters Patent, is:

1. The combination in an internal combustion engine, of a piston cylinder containing an explosion chamber, a carbureter connected with the explosive mixture inlet port of said chamber and having a fuel duct 50 adapted to be alternately connected with a gasoline source of supply and a kerosene source of supply, a cast-metal jacket closed at its ends and having an arm adjacent to one of its ends in communication with the 55 exhaust port of the explosion chamber; said jacket being curved lengthwise through a considerable part of a circle and arranged throughout its length in close proximity to the exterior of the cylinder wall, and a 60 thin-wall pipe arranged lengthwise in the jacket and extended through the closed ends thereof and open at one end to the atmosphere and having its opposite end connected with the carbureter.

2. The combination with the piston cylinder of an internal combustion engine, and a carbureter connected with the explosive-mixture inlet port thereof; of a jacket curved lengthwise through a considerable 70 part of a circle and arranged throughout its length in close proximity to the exterior of the wall of the cylinder and connected adjacent to one of its ends with the exhaust port of the cylinder and having an exhaust 75 outlet adjacent to its opposite end, and a thin wall conduit extending lengthwise through the jacket and open at one end to the atmosphere and having its opposite end connected with the interior of the carbureter. 80

In testimony whereof I affix my signature in presence of two witnesses.

ROCCO DELEWESE.
